ALÉXIS BEURRIER, EDOUARD BIGOURDAN, AND LOUIS LACOIN, OF PARIS, FRANCE.

FLYING-MACHINE WITH REVOLVING WINGS.

1,350,982.

Specification of Letters Patent. Patented Aug. 24, 1920.

Application filed March 24, 1917. Serial No. 157,236.

To all whom it may concern:

Be it known that we, ALÉXIS BEURRIER, EDOUARD BIGOURDAN, and LOUIS LACOIN, citizens of the Republic of France, and residing at Paris, France, 8 Rue François Millet, have invented Improvements in Flying-Machines with Revolving Wings, of which the following is a specification.

This invention has for its object to provide an improved flying machine with revolving wings.

This improved flying machine with revolving wings has generally the form of an aeroplane with the difference however that the vertical screw propeller of the aeroplane is replaced by two large screw propellers which are approximately horizontal.

The manner in which this invention is to be performed will now be more particularly described with reference to the accompanying drawings which illustrate by way of example a practical construction of apparatus according to this invention.

In these drawings:—

Figures 1 and 2 are respectively a front elevation and a plan of an improved flying machine according to this invention.

Fig. 3 is a side elevation of the same.

Figs. 4 and 5 are detailed perspective views of the controlling apparatus, looking parallel to the line of flight.

Figs. 6 and 7 are detailed views respectively of a vertical section, and a plan of various constituent parts of the apparatus serving to effect the control of the propeller vanes.

The same reference numbers indicate the same parts in the various figures.

As shown, the improved flying machine comprises like the ordinary monoplanes, a fuselage or body 1 provided forwardly with a landing carriage 2 and wheels 3, and aft with a horizontal rudder 4, a steering rudder 5 and a skid 6. This fuselage carries likewise the engine 7 and the seats 8 and 9 for the pilot and the passenger respectively.

The vital difference existing between this apparatus and an ordinary monoplane, consists in the fact that the wings or planes of the monoplane are replaced by two screw propellers 10 and 11 having very wide vanes.

The said apparatus may also be constructed according to the type having the rudders in the front and the main set of wings—here the two screw propellers—in the rear. The screw propellers might likewise be placed

midway in the length of the fuselage or body with rudders either at one end or at both ends of the body or frame.

In order to provide the necessary inherent transverse stability, the axles 12 and 13 of these screw propellers are inclined toward each other in such a manner that the screw propellers form together a dihedral angle, as do also for the same purpose the two planes of the main set of wings of most monoplanes. These screw propellers are, moreover, situated at the same height as an ordinary set of wings and constitute revolving wings.

They are driven for instance by the engine 7 which drives bevel gear 14, one of the pinions of which is mounted on a transverse shaft 15 comprising two Cardan couplings 16 and 17 which drive respectively the shafts 40 and 41 that drive respectively two other bevel gears 18 and 19 arranged at the upper parts of the hubs of the screw propellers 10 and 11. These are supported at their lower parts by a transverse beam 34 bearing upon the landing carriage 2.

Each of the screw propellers may have any number of vanes of any shape but is advantageously formed with four vanes capable of assuming various inclinations about their axes, in such a manner as to vary the inclination between the two vanes, this variance differing with different apparatuses.

The control of the inclination of the vanes is preferably effected by means of rocking beams 20 Figs. 5, 6 and 7 arranged at the lower parts of the screw propeller shafts and which may be equal to the number of the vanes or less than this number. Each rocking beam actuates the shrouds 21, 22, 23, 24 fixed to four points of each driven vane, and carries a roller 25 rolling in the annular groove of a collar 26 arranged around and at the lower part of the axle of each propeller.

When the general plane of this collar 26 is at right angles to the axis of rotation of the screw propeller, the inclination of the various vanes is the same and remains such during the entire rotation. By raising or lowering the collar parallel to itself, this inclination can be varied; this is equivalent to increasing or diminishing the pitch of the entire screw propeller.

On the other hand the pilot is able to incline the plane of the collar relatively to the

axis of rotation within limits, by means of connecting rods 32, levers 33 (Fig. 5) and rods 29 which he actuates by means of the hand wheel 31 and the spindle 30 acting 5 upon the ball-jointed connecting rods 27 and levers 28. In this manner the inclination of each vane passes through a series of values capable of varying from a minimum situated at a certain point of the rotation 10 up to a maximum situated at the opposite point. The result of this is that the traction of the screw propeller is decentralized and as this action is produced simultaneously upon the two screw propellers, 15 the result is that the center of support may at the will of the pilot, be shifted toward the right or toward the left, forward or aft, or in any intermediate direction. The pilot is thus able to reëstablish a loss of equilibrium or to modify in any way the position 20 or stability of his apparatus in the air.

This control replaces that of the auxiliary planes and of the stabilizer in aeroplanes, and moreover allows by inclining the axis 25 of the entire machine toward one side or the other of causing the said machine to slide toward the side on which it has been inclined.

In particular, for forward travel the machine is inclined forward. The traction of 30 the screw propellers has then a horizontal component which pulls the apparatus toward that side. The rudders provided aft of the fuselage then operate as in an aero- 35 plane.

If on the contrary the machine is inclined aft, a braking action is produced and the apparatus can then cease to advance and it can hover. It can also rise or descend vertically, rise off the ground or alight thereon, 40 owing to the variations of the pitch of the screw propellers which are produced by means of the hand wheel 31 mounted on the upper end of the spindle 30. This hand wheel in turning, screws or unscrews the spindle in a nut 42 which is carried by the Cardan coupling 43. This causes an upward or a downward movement of the crosshead 44 which through the connecting rods 27 and the levers 28, actuates the rods 29 which act through the bell crank levers 33 upon the rods 32 that operate the collar 26 (see Figs. 4, 5 and 6.)

In particular, in the case of a break down 55 of the engine, the vanes being set flat, become then simple supporting surfaces like the wings of a monoplane. Their area may even be greater than that of the said wings in order to compensate for the inferiority 60 due to their shape which is slightly less favorable for supporting than the shape of a single elongated rectangle. The machine will therefore descend by planing down, and owing to its rudders, it can land at the 65 best accessible point chosen by the pilot.

If it is desired to descend vertically or obliquely by slowing the rotation of the propellers, the vanes may be inclined in the direction opposite to their ascent inclination and they may then continue to 70 revolve in their usual direction, but, being braked either by the engine or by a special brake, they will slow the descent.

In certain cases it will be an advantage 75 to mount the two screw propellers on one and the same axis about which they will revolve in opposite directions. One of these screw propellers can then be provided with this device for affording stability and safety. In this arrangement there will only be one 80 collar supported at three points. It will therefore be able to assume an inclination in any direction on being controlled by the hand wheel spindle whose crosshead will then have likewise three arms. The inclinations of the hand wheel spindle, whatever 85 they may be, will have a tendency to incline the common axis of the two screw propellers in the same way. The hand wheel will control the pitch of the screw propeller 90 acted upon by the collar, and can in case of necessity, do away with all inclination. This screw propeller must have a large area in order to be able to support the machine 95 while it is planing down.

For other uses, and in particular for aerobuses, it will be necessary to mount four screw propellers at the apex of a rectangle or of a trapeze. The same mechanism for providing stability and security is also 100 applicable but without it being absolutely necessary to make the collars capable of being inclined. Each of these collars will then need only to move up and down parallel to itself along the axle. The changes 105 of pitch will then affect the entire screw propeller and not each vane independently.

Having now particularly described and ascertained the nature of our said invention, and in what manner the same is to be performed, we declare that what we claim is:—

1. The combination with a flying machine having revolving wings in the form of screw propellers mounted on separate axes, of a controlling apparatus comprising a member 115 which is non-rotatable relatively to the propeller shaft but capable of inclination relatively to said shaft and capable of movement parallel thereto, a lever one end of which controls the inclination of the vane and rotates therewith engaging in said member.

2. The combination with a flying machine having revolving wings in the form of screw propellers mounted on separate axes, of a controlling apparatus comprising a member 125 which is non-rotatable relatively to the propeller shaft but capable of inclination relatively to said shaft and capable of movement parallel thereto, a lever to control the inclination of the vanes and rotating there- 130

with, one end of said lever engaging in said non-rotatable member, connecting members between said lever and said vanes, and means for actuating said non-rotatable 5 member so that its movements in inclination to the propeller shaft and its movements parallel thereto, may be effected either simultaneously or separately.

3. A flying machine with revolving 10 wings, having generally the form of a monoplane comprising two screw propellers mounted on separate axes which are approximately vertical; these screw propellers replacing the wings of a monoplane as regards position and area, and therefore allowing either of slowing the descent or, when 15

set flat, of enabling the machine to plane down in the case of stoppage of the engine, such propellers having their vanes controlled individually in such a manner as to 20 provide the necessary stability in every direction and in every position whereby the axis of the machine may be inclined as desired.

In witness whereof we have hereunto set 25 our hands in presence of two witnesses.
